UNITED STATES PATENT OFFICE.

JOHN SEILER, OF UNION HILL, NEW JERSEY.

AEROPLANE.

No. 927,605.

Specification of Letters Patent.

Patented July 13, 1909.

Application filed August 5, 1908. Serial No. 447,032.

To all whom it may concern:

Be it known that I, JOHN SEILER, a citizen of the United States of America, and a resident of Union Hill, county of Hudson, State of New Jersey, have invented certain new and useful Improvements in Aeroplanes, of which the following is a specification.

My invention relates to flying machines or air ships, and comprises certain improvements in that type of machine known as the aeroplane.

The best form of apparatus embodying my invention at present known to me is illustrated in the accompanying three sheets of drawings, in which:

Figure 1 is a plan view and partial section of the apparatus on line 1—1 of Fig. 3. Fig. 2 is a side elevation and partial section on line 2—2 of Fig. 3. Fig. 3 is a cross section on line 3—3 of Fig. 1.

Through the drawings, like reference figures indicate like parts.

1 and 2 represent longitudinal bracing pieces extending lengthwise of the machine, 25 1 being at the left hand and 2 at the right hand, looking at Fig. 3. Preferably these braces are tubular in shape and are coned slightly from the center toward each end.

3, 3, &c. represent radial braces or arms 30 extending from the longitudinal brace 1, and 4, 4, are similar arms or braces extending from longitudinal brace 2.

5, 5, represent cords, wires or light rods connecting the extremities and intermediate 35 points of the radial arms lying in the same cross sectional plane.

6, 6, represent cords, wires or light rods connecting the extremities and intermediate points of the different sets of radial arms 3 40 and 4 in planes parallel to the longitudinal braces 1 and 2. There are a series of vertical central braces indicated at 7 in Fig. 3 and a series of tension members 10, 10, extend from the front and rear sets of radial 45 arms 3 and 4 to the front and rear extremities of the longitudinal braces 1 and 2. On the cords 6, 6, are stretched a series of cloths 8, 8, or other thin, strong material which forms a series of supporting planes 50 for the aeroplane. Preferably a portion of these cloths are stretched around to form a series of closed figures of quadrilateral cross section, as indicated in Fig. 3. Each of these therefore forms practically what is 55 popularly known as a box kite and the whole

machine consists essentially of a series of such box kites supported by a skeleton frame. On the lower portion of the strong skeleton frame thus formed, is supported a small platform 9, and under the frame are 60 wheels 11, 11, just forward of the mid section of the frame and a single wheel 12 at the rear. The wheels 11, 11, are dropped a little lower below the frame than the wheel 12, so that when the machine is run along a 65 horizontal surface it will point upward slightly and tend to rise by the action of the aeroplanes.

On the platform 9 I have indicated any convenient form of motor 13 which may be 70 geared to the propellers 14 and 15 in any convenient manner to produce rotation of the same in opposite directions as by the belt 16 extending to the propeller 14 and the cross belt 17 extending to the propeller 15. 75 These propellers are journaled on the longitudinal braces 1 and 2 and are located between two closely adjacent sets of radial arms 43 and 44 (see Fig. 1). The longitudinally extending cords 5, 5, and 6, 6, which 80 would otherwise interfere with the rotation of these propeller wheels are discontinued between these two sets of radial arms 43 and 44 so as to form a compartment or well in which the propeller wheels may freely 85 revolve.

18 represents a vertical hinged rudder at the rear of the machine which is cut away at 18^a to clear the cross brace 34 connecting the rear ends of the longitudinal braces 1 90 and 2. This rudder is controlled by the tiller rope 20 extending around the guide pulleys 21, 21, to the foot tiller 22 which is pivoted at 23 in a convenient position to receive the foot of the operator in a manner 95 similar to that employed in racing shells.

19 is a rudder pivoted upon a horizontal hinge on the cross brace 35 at the front end of the machine and connected by the tiller rope 24 passing around guide pulleys 25, 100 25, to tiller 26, which has a horizontally extending pivot 27.

29, 29, represent pairs of balancing fins which are freely pivoted along their upper edges to the upper edges of pairs of inclined 105 planes 28, 28 formed by certain of the cloths 8, 8, in the particular construction illustrated in the drawing, which are of approximately the same size and inclined inwardly at equal angles to the central plane of the machine. 110

30 is a link connecting two hinged fins so that they will swing always parallel one to the other.

32, 32, indicate a pair of conveniently arranged tillers pivoted on the longitudinal braces 1 and 2 respectively and connected by links 31, 31, with the swinging fins 29, 29, so that the position thereof may be positively controlled by the operator if desired.

10 33, 33, represent a series of air pockets preferably in the form of conical sections which open toward the rear of the machine while the apex of the cone is toward the front. These pockets are arranged on the 15 under side of certain of the supporting planes, as indicated in the drawings.

Such being the construction of my apparatus, the mode of operation is as follows: The motor being set in operation and the 20 operator taking his position upon the platform 9, the machine will be driven forward upon the wheels 11 and 12, pointing slightly upward and will soon be lifted by the aeroplanes clear of the ground. By raising or 25 lowering the tiller 26, the operator controls the forward rudder 19 and causes the machine to point upward or downward. By inserting his foot in the foot tiller 22 and swinging the same to the right or left, he 30 manipulates the rear rudder 18 and causes the machine to point to the right or left. Any transverse currents of air striking the machine on either side will tend to swing the balancing fins 29, 29, toward and from the 35 adjacent inclined planes 28, 28, and thereby modify the effective area of the supporting planes so as to automatically counteract any tipping action which might otherwise result. That is to say, if a cross current strikes 40 the left hand side of the machine, looking at Fig. 3, it will tend to swing the fin on that side up against the adjacent plane 28, as indicated in dotted lines and thereby reduce the effective area of said left hand fin to zero, while the right hand fin will be forced 45 out in the position shown in dotted lines and brought into effective position where it will be acted on by the current of air passing from the left to right so as to lift the right hand side of the machine and thereby overcome any tipping action. If the action is 50 not entirely automatic, or if the operator desires to vary the supporting action of the planes to correspond to any shifting of the 55 center of gravity of the machine, the fins can be positively controlled by the operator seizing either one of the tillers 32, 32. As indicated, the engine being to the rear of the medial cross section of the apparatus, there 60 will be a tendency of the machine to tip backward slightly and run backward on the supporting planes in case the propeller wheels are stopped. The too rapid running 65 backward of the machine in case of stoppage from accident to the machinery is prevented

by the air pockets 33, 33, which present a considerable resistance to such backward running of the machine, but would present little resistance to the forward motion of the machine when the engine is working. 70 These pockets would therefore have a parachute-like action in breaking the descent of the machine in case the engine was shut down. The inclination of the machine while running backward would of course be also 75 controlled by the forward rudder 19.

The advantages of my invention comprise its stability against tipping to forward or rear resulting from its great length and large expanse of aeroplane along the line of 80 its length, and the great supporting power compared with weight due to the light but strongly braced skeleton frame carrying a large number of individual box kites, as described; the great rigidity with light weight 85 and small air resistance given by the construction embodying the longitudinal braces, radial arms, longitudinal and cross cords, and inclined tension cords at front and rear; the arrangement of the propellers medially 90 of the frame in line with a series of box kites, before and behind, which form guiding passages for the air and give great steadiness to the aeroplane and added propulsive effect to the propeller wheels, the air 95 being forced to travel in a straight line parallel to the axis of the propeller wheels, and the blades of said wheels being thereby enabled to act upon the air with the greatest possible efficiency; and finally the convertible automatic or controllable action of 100 the hinged fins by which all conditions tending to produce side tipping of the apparatus may be met.

Of course numerous changes in the details 105 of construction could be made without departing from the principle of my invention. Other arrangements of driving gearing could be substituted for that shown. The number of balancing fins and air pockets could 110 be varied. The arrangement of steering gear could be changed, and other similar modifications made to suit special conditions without varying the essential principles of 115 operation.

Having, therefore, described my invention, I claim:

1. In an aeroplane the combination with a plurality of longitudinally extending bracing members, of a plurality of arms radiating therefrom, cords extending longitudinally and connecting the corresponding points in corresponding arms, and a series of planes extending from one to another of said cords.

2. In an aeroplane the combination with a plurality of longitudinally extending bracing members, of a plurality of arms radiating therefrom, cords extending longitudinally and connecting the corresponding 125 130 135

points in corresponding arms and a series of planes extending from one to another of said cords to form a series of boxes open at front and rear.

5 3. In an aeroplane the combination with an open framework whose greatest dimension is in the line of flight, of a plurality of box kites set in said framework parallel to its greatest dimension.

10 4. In an aeroplane the combination with two longitudinally extending bracing members, of a plurality of sets of arms radiating therefrom, cords connecting the outer extremities of said arms, a series of planes

15 supported on said cords, a propeller wheel journaled on each bracing member, said wheels being of opposite pitch and located between two closed adjacent sets of arms, and means for causing said propeller wheels 20 to rotate simultaneously in opposite directions.

5. In an aeroplane the combination with two longitudinally extending bracing members, of a plurality of sets of arms radiating 25 therefrom, cords connecting the outer extremities of said arms, a series of planes supported on said cords and a series of tension members extending from the extremities of the arms of the front and rear sets 30 to the front and rear extremities of the bracing members.

6. In an aeroplane the combination with an open framework which is longer than it is wide or high, of a series of planes supported thereon and a plurality of pockets formed on the under side of some of said planes, said pockets opening rearward, the center of gravity of said aeroplane being to the rear of its mid section.

40 7. In an aeroplane the combination with the frame and supporting planes including a pair of oppositely disposed planes one on each side of the frame inclined downwardly and inwardly, of a pair of loose balancing

45 fins of approximately the same size as the inclined planes hinged one to the upper edge of each inclined plane, and hanging down-

ward, and means holding said balancing fins parallel to one another as they swing.

8. In an aeroplane the combination with 50 the frame and supporting planes including a pair of oppositely disposed planes one on each side of the frame inclined downwardly and inwardly, of a pair of loose balancing fins of approximately the same size as the 55 inclined planes hinged one to the upper edge of each inclined plane, and hanging downward, and means holding said balancing fins parallel to one another as they swing, together with mechanism for positively swinging said fins.

9. In an aeroplane the combination with the frame and supporting planes of pairs of balancing fins hinged to opposite sides of the frame, and means for causing one fin of 65 each pair to extend away from a supporting plane whenever the other fin of that pair is forced toward a supporting plane, whereby the supporting surface is increased on 70 one side of the frame and not on the other.

10. In an aeroplane the combination with a frame and a series of supporting planes arranged to form a series of passageways for the air longitudinally of the frame, of one or more propeller wheels located medially 75 of the frame, each having its circle of revolution within the cross section of the frame, and means for revolving said propeller wheels.

11. In an aeroplane the combination with 80 the frame and supporting planes including a pair of oppositely disposed planes one on each side of the frame inclined downwardly and inwardly, of a pair of loose balancing fins hinged one to the upper edge of each inclined plane, and hanging downward, and means holding said balancing fins parallel to 85 one another as they swing.

Signed at New York, N. Y. this 1st day of August, 1908.

JOHN SEILER.
